UNITED STATES PATENT OFFICE.

LYSANDER BUTTON AND ROBERT BLAKE, OF WATERFORD, NEW YORK.

IMPROVEMENT IN PUMPS.

Specification forming part of Letters Patent No. **35,079**, dated April 29, 1862.

To all whom it may concern:

Be it known that we, LYSANDER BUTTON and ROBERT BLAKE, of Waterford, in the county of Saratoga and State of New York, have invented a certain new and useful Improvement in Pumps; and we do hereby declare that the following is a full, clear, and exact description of the construction and operation of the same, reference being had to the accompanying drawings, which make a part of this specification, in which—

Figure 1 is a front elevation of the pump and its connections; and Fig. 2 is a vertical cross-section of the same, the same letters having reference to like parts in both figures.

The nature of our invention consists in operating, by means of a double crank, two valve-pistons in one cylinder, one piston-rod being hollow and the other solid, and working inside of and through the hollow rod, the double crank being so constructed and connected to the piston-rods as to give the pistons motion in opposite directions when the crank is revolved, thereby producing, in a direct and simple form, a double-acting pump with straight water-ways, and consequently of superior power.

The construction is as follows: A is the pump-cylinder, in which we arrange two pis-

tons, B and C, attached to and operated by means of a hollow rod, D, and rod E, passing through said hollow rod, said rods respectively being connected by rods F G to double cranks H I, or eccentrics, or their equivalents, which are constructed and arranged to give motion to the pump-pistons in opposite directions, and consequently producing a double-acting pump, the pistons having suction and discharge alternately and uniform motion by means of the double cranks. The water passes through openings a a in the respective pistons, which are closed by valve-plates b b. When the pump is at rest, the water is retained in the same by means of the foot-valve J.

Having thus described our improved pump, what we claim is—

The two pistons operating in one cylinder by means of the two piston-rods, one passing through the other, combined with and operated by the double crank, in the manner and for the purpose set forth.

LYSANDER BUTTON.
ROBERT BLAKE.
